UNITED STATES PATENT OFFICE.

FRANK MICHELBACH, OF DEL RAY, VIRGINIA.

DISPLAY RACK.

Application filed April 7, 1922. Serial No. 550,386.

This invention relates to display racks and more particularly to racks for displaying rolled rugs in upright positions.

It has been found from experience that it is highly desirable to obtain a rug display rack that will display the rugs in separate groups in order that rugs of different classes may be positioned in different groups, thereby enabling the merchant to readily locate 10 rugs of selected type in predetermined groups, and an object of this invention is to provide a rug display rack comprising means for displaying rolled rugs in upright positions and arranged in radially disposed 15 groups.

Another object of this invention is to provide a rug display rack comprising a platform and means for displaying rolled rugs in separate groups of such configuration as 20 to divide the platform into separate segmental areas for the reception of additional articles of merchandise or ornamentations to be displayed.

A further object of the invention is to 25 provide a rug display rack including a supporting base and a rotary platform cooperating with the base, there being means for readily centering the platform upon the base, thereby enabling unskilled persons to 30 move the device from place to place and quickly assemble it without danger of dislocation of its cooperating components.

An additional object of this invention is 35 to provide a rug display rack of generally improved construction, whereby the device will be simple, durable and inexpensive in construction, as well as convenient, practical, efficient and serviceable in its use.

With the foregoing and other objects in 40 view which will appear as the description proceeds, the invention resides in the combination and arrangement of parts and in the details of construction hereinafter described and claimed, it being understood that 45 changes in the precise embodiment of the invention herein disclosed, may be made within the scope of what is claimed, without departing from the spirit of the invention.

The invention has been illustrated in its 50 preferred embodiments in the accompanying drawings wherein:—

Figure 1 is a perspective view of the invention.

Figure 2 is a central vertical section, parts 55 appearing in elevation, and showing the rugs in their supported position.

Figure 3 is a top plan view.

Figure 4 is a horizontal sectional view taken on a line 4—4 of Figure 2, but showing ornamental members positioned in the 60 segmental areas upon the rotary platform; and

Figure 5 is a central vertical sectional view taken through the bearing member.

Referring to the drawings, there is shown 65 an annular base 10 supporting an annular track or race-way 11. A rotary platform 12 is provided and is supported by a plurality of anti-friction devices 13, such as rollers or ball members, and these anti-friction devices cooperate with the track 11 to support the platform 12 for free rotary movement upon the base 10. An axial shaft 14 is provided and is secured adjacent its lower end to an upstanding sleeve 15 of a 70 coupling member, and the coupling member is in turn secured to the center of the platform 12 by means of securing devices 16 which extend through the platform and a flange 17 extending radially from the lower 75 end of the sleeve 15.

In order to support the rugs, there is provided a supporting member 18 having a central hub or sleeve 19, which is secured to the upper end of the shaft 14 by means of suitable securing devices. A plurality of radial 80 arms 20 extend from the hub 19 and each arm has a plurality of opposed arcuate recesses 21 formed in its opposed longitudinal edges.

The rotary platform 12 is also provided with radially extending arms 22 and each arm 22 has opposed recesses 23 formed in its longitudinal edges, the recesses 21 and 85 23 being disposed in vertical alignment for the reception of the periphery of the rolled rugs, thereby supporting these rugs in an upright or vertical position. Chains or other flexible elements 24 are secured to the central portion of the supporting member 18, by means of screws or other securing devices, while upstanding pins or hooks 25 are carried by the lateral fingers or extensions 26 formed at the outer ends of the radial arms 20. These chains engage the rugs and hold 90 them within their respective recesses, and the outer terminals of the chains are secured to the lateral extensions 26 by placing a selected link of each chain over a pin 25, thereby securing each chain in engagement 95 with the rugs.

Brace rods 27 connect the outer terminals of the arms 20 with the rotary platform 12,

these rods being secured at their opposed ends to the arms 20 and the platform 12 by means of studs and nuts or any suitable securing devices.

5 In order to center or axially align the rotary platform with respect to the annular base, there is provided a centering bearing member or pedestal which comprises a housing 28 that is provided with an axial bore 29 and this bore is enlarged at 30 to provide an annular shoulder 31. A case-hardened plate 32 is positioned within the bore 29 to cooperate with a case-hardened thrust bearing member 33 which has a reduced shank 34 extending therefrom, thereby providing an annular shoulder 35. This shank 34 is forced into the lower end of the tubular shaft 14 and the shoulder 35 engages the lower end of this shaft, thereby providing a 10 rigid structure to receive the vertical stress or thrust imparted by the central portion of the rotary platform to the central bearing member. The shaft 14 is held against lateral movement by means of a ball bearing device including inner and outer annular members 36 and 37, having complementing race-ways for the reception of balls 38, and this complete bearing device is held seated upon the shoulder 31 by means of set screws 39. Thus it is obvious that the vertical thrust exerted by the rotary platform and its components is received by the annular base 12 and the axial bearing 28, while the lateral stress is received by the annular ball bearing structures 36 and 37.

To insure the axial alignment of the bearing housing 28 relative to the base 10, there are provided spacing links 40 of predetermined lengths and each link is pivotally secured at its outer end to the annular base 10 in any suitable way, as shown at 41, while its inner terminal is detachably secured to the housing 28 by bending this terminal perpendicular to the link and extending this perpendicular portion 42 through an aperture 43 formed in a web 44 extending radially from the pedestal 28. There are preferably four webs and links, so that when the links are in position, it is manifest that the bearing housing 28 will be accurately positioned in the center of the annular base 10, thereby insuring the axial alignment of the rotary platform relative to the annular base.

55 If desired the rotary platform may be mechanically rotated, and to this end the platform 10 has a gear 45 secured to its lower face and a pinion 46 meshes with this gear. The pinion 46 is carried by a shaft 47 which is mounted for rotation within bearings 48 and this shaft may be driven from any suitable source of power, not shown.

60 65 In operation, the device may be readily assembled by simply placing the links 40 in

position thereby centering the bearing housing or pedestal 28, and then the pedestal 28 may be readily secured to the floor by lag screws or other securing devices. Now the rotary platform and its components are mounted upon the base and the device is ready for use. Thus it is obvious that an unskilled person may readily move the device from place to place as desired and properly assemble it, because the links 40 insure the true centering of the pedestal, thereby obviating the necessity for the use of gages or other measuring instruments.

70 The rugs are secured in position in radially disposed groups, thereby permitting 80 rugs of different classes as to quality or design to be positioned in selected groups, thus enabling the merchant to quickly locate a selected rug in its proper group, and also enabling the merchant to direct attention to 85 an entire group by means of properly worded placard or sign without confusing these rugs with rugs of a different class that are located in a separate group.

90 By supporting the rugs upon the platform in radial groups, the platform is consequently divided into separate segmental display areas or spaces 49 and these areas are utilized to display smaller miscellaneous articles of merchandise under certain conditions; and as shown in Figures 2 and 3, these areas are used to display smaller rolled rugs, which owing to their relatively small size do not interfere with the proper display of the larger rugs.

95 When it is desired to present a window display, then ornamental pieces may be placed upon the platform within the segmental areas 49, and as shown in Figure 4 these areas are used to display flower vases 105 which obviously add to the attractiveness of the device.

Having thus described the invention, what is claimed as new is:—

1. A rug display rack including a platform, an axial shaft carried by the platform, a supporting member secured to the shaft and spaced from the platform, radially disposed arms carried by the supporting member, said arms having opposed longitudinal edges for the reception of rolled rugs, and means for securing rolled rugs to the said arms.

2. A rug display rack including a base, a platform rotatably mounted upon the base, an axially disposed shaft carried by the platform, a bearing member rotatably receiving the terminal of the said shaft, and spacing members attached to the base and detachably connected to the said bearing member, thereby centering the bearing member relative to the base and insuring the axial alignment of the platform with respect to the base.

3. A rug display rack including a plat-

form, a shaft carried by the platform, a supporting member carried by the shaft and spaced from the platform, radially disposed arms carried by the supporting member, said arms having recesses formed in the longitudinal edges thereof for the reception of rolled rugs.

4. A rug display rack including a platform, a shaft carried by the platform, a supporting member carried by the shaft and spaced from the platform, radially disposed arms carried by the supporting member, the longitudinal edges of the said arms positioned to engage and support rolled rugs in upright position upon the platform.

5. A rug display rack including a platform, a shaft carried by the platform, a supporting member carried by the shaft and spaced from the platform, radially disposed arms carried by the supporting member, said arms having recesses formed in the longitudinal edges thereof for the reception of rolled rugs, and means for holding the rugs in the said recesses.

25 6. A rug display rack including a platform having recesses arranged in radial groups thereon, a shaft carried by the platform, a supporting member carried by the shaft and spaced from the platform, radially disposed arms carried by the supporting members, said arm having recesses formed thereon in alignment with the platform recesses to receive rolled rugs therein.

35 7. A rug display rack including a platform, an axial shaft carried by the platform, a supporting member carried by the shaft and spaced from the platform, radially disposed arms carried by the supporting member, said arms having separate recesses

formed in each longitudinal edge for the reception of rolled rugs, and a common flexible member for securing the rugs in the separate recesses of each longitudinal edge of the radially disposed arms.

8. A rug display rack including a platform having recesses arranged in radial groups thereon, a shaft carried by the platform, a supporting member carried by the shaft, radially disposed arms carried by the supporting member and positioned in alignment with the said radial groups of recesses to support rolled rugs in upright position upon the platform.

9. A rug display rack including a platform having recesses arranged in radial groups thereon, a shaft carried by the platform, a supporting member carried by the shaft and spaced from the platform, radially disposed arms carried by the supporting member, said arm having recesses formed therein in alignment with the said platform recesses to receive rolled rugs therein, and means for holding the said rugs in the recesses of the radial arms.

10. A rug display rack including a platform having recesses arranged in radial groups thereon, a shaft carried by the platform, a supporting member carried by the shaft, radially disposed arms carried by the supporting member and positioned in alignment with the said radial groups of recesses to support rolled rugs in upright position upon the platform, and means for securing the rugs to the said arms.

In testimony whereof I affix my signature.

FRANK MICHELBACH.
